(57) CLAIM

The ornamental design for a combined wrist container and watch, as shown and described.

DESCRIPTION

FIG. 1 is a perspective view of a combined wrist container and watch shown in an open position;

FIG. 2 is a side view thereof;

FIG. 3 is a back view thereof;

FIG. 4 is a front view thereof;

FIG. 5 is a top view thereof;

FIG. 6 is a bottom view thereof; and,

FIG. 7 is a perspective view of the combined wrist container and watch shown in a closed position.

The hour and minute hands, which are shown in broken lines in FIGS. 3 and 7, are for illustrative purposes only and form no part of the claimed design.
